DESIGN FOR A BRACKET FOR SUPPORTING WIRES

Charles Peckerman, New York, N. Y., assignor to
Everbest Engineering Corp., New York, N. Y., a
corporation of New York

Application February 6, 1945, Serial No. 117,789

Term of patent 14 years

(Cl. D26—1)

To all whom it may concern:

Be it known that I, Charles Peckerman, a citizen of the United States of America, residing at 920 Riverside Drive, Borough of Manhattan, city and State of New York, have invented a new, original, and ornamental Design for a Bracket for Supporting Wires, of which the following is a specification, reference being had to the accompanying drawing forming a part thereof, and wherein

Fig. 1 is a front view of a bracket for supporting wires showing my new design,

Fig. 2 is a side view thereof, and

Fig. 3 is a rear view thereof.

I claim:

The ornamental design for a bracket for supporting wires, substantially as shown.

CHARLES PECKERMAN.
